UNITED STATES PATENT OFFICE.

JOSEPH W. GOSLING, OF SCHENECTADY, NEW YORK, ASSIGNOR TO GENERAL ELECTRIC COMPANY, A CORPORATION OF NEW YORK.

DESIGN FOR A LIGHTING FIXTURE.

Application filed June 12, 1924. Serial No. 9,864. Term of patent 14 years.

To all whom it may concern:

Be it known that I, JOSEPH W. GOSLING, a citizen of the United States, residing in Schenectady, county of Schenectady, State of New York, have invented a new, original, and ornamental Design for Lighting Fixtures, of which the following is a specification, reference being had to the accompanying drawing, forming a part thereof.

The accompanying drawing is a perspective view of my new design.

I claim:

The ornamental design for a lighting fixture as shown.

In witness whereof, I have hereunto set my hand this 11th day of June, 1924.

JOSEPH W. GOSLING.
